(57) **CLAIM**

The ornamental design for a gas composition detection device and pipe assembly, as shown and described.

DESCRIPTION

This invention was made with government support under SBIR Phase II Award No. 1632439 awarded by the National Science Foundation. The government has certain rights in the invention.

FIG. 1 is a bottom, rear, right side perspective view of a gas composition detection device and pipe assembly showing the claimed design;

FIG. 2 is a top, rear, left side perspective view thereof;

FIG. 3 is a front view thereof;

FIG. 5 is a left side view thereof;

FIG. 6 is a right side view thereof;

FIG. 7 is a top view thereof;

FIG. 8 is a bottom view thereof;

FIG. 9 is a top, front, left side perspective view thereof, with the housing of the gas composition detection device removed; and,

FIG. 10 is a bottom, front, right side perspective view thereof, with the housing of the gas composition detection device removed.

The broken lines in the figures show portions of the gas composition detection device and pipe assembly that form no part of the claimed design.
